UNITED STATES PATENT OFFICE.

JOHN S. CRAWFORD, OF NEW LONDON, CONNECTICUT.

SAFETY DEVICE FOR RAILWAYS.

1,221,690.

Specification of Letters Patent.

Patented Apr. 3, 1917.

Application filed March 16, 1915, Serial No. 14,797. Renewed October 26, 1916. Serial No. 127,829.

To all whom it may concern:

Be it known that I, JOHN S. CRAWFORD, a citizen of the United States, resident at New London, in the county of New London, 5 in the State of Connecticut, have invented a certain new and useful Improvement in Safety Devices for Railways, of which the following is a specification, reference being had to the accompanying drawings.

10 The immediate object of my invention is to provide simple but effective mechanism for setting the brakes, and for simultaneously shutting off the steam, or electric power as the case may be, in railway trains 15 whenever danger signals are set against said train; said safety mechanism being, preferably, attached to the locomotive and being adapted to work equally effectually whether the train is running ahead or backward.

20 My said invention is illustrated in, and by, the annexed drawings, in which Figure 1 is a side elevation of the several elementary features of my invention showing the said elements in approximately the relations which they would bear to each other 25 when assembled and mounted on the locomotive and ready for service. Fig. 2 is a relatively enlarged view of the control cylinder 64 and its immediate connections, the 30 cylinder proper being shown in vertical, longitudinal, central section, and Fig. 3 is a transverse, vertical, sectional view of the same taken on the line 4—4 of the Fig. 2. Fig. 4 is a vertical, longitudinal, sectional 35 view of the relief valve 57 and test cylinder 53, and Fig. 5 is a similar view of the main supply shut-off 49. In the Fig. 6 I have illustrated the engineer's reverse lever, partly in section to aid in explaining the 40 means provided for unlatching said lever automatically and simultaneously with the automatic setting of the air brakes.

The numeral 45 indicates a compressed air receiver and 46 the train (air) pipe, the 45 said pipe and receiver being connected by a three section pipe 47, 47^a and 47^b which includes the engineer's valve 48 and what I term a "main supply shut-off valve" 49 which is normally open to the pipe sections 50 47^b—47^a as seen in the sectional view Fig. 6 and so that air may pass direct from the receiver 45 to the train air pipe 46 whenever the valve 48 is operated by the engineer.

The customary reversing lever is shown 55 at 50 and the customary steam throttle lever

and valve rod are shown at 51 and 52 respectively.

The numeral 53 denotes a test cylinder which is connected by a pipe 54 with the pipe section 47^b already referred to; said 60 pipe 54 including a hand-operable valve 54^a by means of which the engineer may connect the compressed air supply in receiver 45 with the test cylinder 53; said test cylinder being shown, enlarged and partly in 65 central, vertical, section in Fig. 4, to which reference is now directed. The test cylinder 53 contains a piston whose rod 53^a is rigidly connected to the stem 57, and which, therefore, operates on the admission of pressure 70 thereto by the manual actuation of the valve 54^a to raise the valve block 58 to establish communication between the elements 46^b and 63.

The numeral 55 identifies an idle roll 75 which is located below the locomotive, in position to be engaged, and forced upwardly by contact with a cam block 21 which is located between the traction rails and is adapted to be elevated whenever a signal 80 is set against an approaching train. The roll 55 is carried by a substantial frame 56 which is mounted on the lower end of a plunger rod 57 which is slidably mounted in the housing 53^a to which the test cylinder 53 is attached and has fixed on its upper end portion a cut-off valve block 58 which is arranged to slide in a valve housing 59 which extends in a direction at right angles 85 to the plane of movement of the plunger-rod 57 and its attached valve-block 58. The train air pipe 46 enters the housing 59 at 46^a and is normally cut off from the chamber or housing 59 by the valve-block 58 as seen in the said Fig. 4. When, however, the 90 block 58 is forced upward, by reason of the roll 55 contacting with the cam-block the air from the train pipe is permitted to rush 95 into the housing 59 and, engaging a piston 60, forces said piston and an attached cut-off valve 61 forward against the opposing force of a spring 62. The valve 61 serves as a cut-off between the opposing ends of a branch pipe 46^b, which connects the train 100 pipe with the housing 59, and a pipe 63 which connects said housing with what I term a "control cylinder" which is indicated by the numeral 64, the said control cylinder 105 being shown on an enlarged scale in Fig. 2 of the annexed drawings. The said control 110

cylinder is formed with a cylindrical chamber 64^a in which is slidably seated a piston 64^b which is connected by a piston rod 65 and a link 66 with the reversing lever 50, 5 and the said control cylinder is provided at its opposite ends with inlet ports 64^c and 64^d which are, respectively, connected with the air pipe 63 by branch pipes 63^a and 63^b.

The port 64^c is normally closed by a 10 spring-pressed valve 67 and the port 64^d is normally closed by a spring-pressed valve 68, each of the said valves (67—68) being attached to a rod 69 which carries an idle roll 70. One of said rolls lies in the path 15 of a cam block 71 and the other of said rolls lies in the path of a cam block 72, said cam blocks being carried by a bar, or rod, 73 which is adapted to slide longitudinally in bracket bearings 74 and is connected to the 20 piston rod 65 by an arm 75 in such manner that, when the piston is moved by the setting of the reversing lever 50, the cam-bar 73 will be correspondingly moved, and the engagement and disengagement of the cam 25 blocks 71—72 with the rolls 70 will result in closing the last opened port 64^c or 64^d, as the case may be, and the opening of the other of said ports, thus cutting off the entrance of air at one end of the cylinder 64 30 and admitting air to said cylinder at the other end as will be understood by reference to the said Fig. 2. Connected to the control cylinder 64 at or near its opposite ends are pipes 76—77 which lead into the cylinder 35 78 of a relay valve which includes a piston 79, that is slidably mounted in said cylinder 78, and leading outward from said cylinder is a pipe 80 which extends rearward to a point near the reverse lever 50, as here illustrated 40 where it is connected, by a flexible pipe section 80^a with a pipe 80^b that is secured to the reversing lever 50 and discharges into a cylinder 50^a in which is a piston 50^b that is secured to the rod 50^c 45 which latter serves to latch the lever 50 in its operative position, the arrangement of the described elements being such that the air under pressure, entering cylinder 50^a will engage the piston 50^b and force said piston and the connected rod 50^c longitudinally sufficiently to release the end of the rod 50 from engagement with the notched arc 81. The pipe 80 is connected by means of a 50 nipple 82 with the main supply shut-off 55 valve 49 in such a manner that, when air is released from the relay valve 78 and passes through the pipe 80, it will engage a piston 49^a and force the latter rearward, carrying with it a valve 49^b and thus closing a port 60 49^c which connects the pipe section 47^a with the pipe section 47^b, thus cutting off the passage of air from the receiver 45 to the train pipe for the time being or, more properly, to the engineer's valve 48 if the latter is closed. 65

Having now described generally the principal elementary features of my safety system, and the way in which they are connected, I will now describe briefly the operation of the same.

Immediately upon the setting of a stop signal against the train the cam-block 21 is 70 elevated to its operative position in the path of the roll 55 carried by the locomotive. When the said roll contacts with the cam it (the roll) is forced upward carrying with it the valve-block 58 which permits air to rush in from the train pipe 46, thus moving the piston valve 61 and opening pipes 46^b and 63 to each other and permitting the air to pass 75 on to the control cylinder 64.

If the reversing lever 50 is set to go ahead, as seen in Fig. 1 the piston 64^b in cylinder 80 64 will be in the position seen in full lines in Fig. 2 and the port 64^c will be open thus 85 allowing air to pass through the branch 63^a, and through said port 64^c, and thence on through pipes 76 and 80 to the reversing lever latch-releasing device, as described and, so soon as the said latch is released the 90 air pressure in the control cylinder 64 will force piston 64^b rearward and, through the piston rod 65 and the link rod 66, the reverse lever 50 is swung back to its reverse position. Simultaneously with this action the 95 brakes are set in the customary manner by reason of the reduced pressure in the train air pipe, the usual venting action for the train-pipe line to the atmosphere being provided for, although not herein shown. 100

In order to also, simultaneously, shut off the steam from the cylinders, assuming that my described system is applied to a steam operated locomotive, I provide a steam-control cylinder 83 in which is a piston 84 105 whose rod 85 is linked to the throttle lever 51 and I connect the cylinder 83 with the pipe 63 by a pipe 80' as here shown, in such manner that, when my described system is started into action air, under pressure, will 110 pass through the pipe 80 and, engaging the piston 84, will operate to rock the throttle lever 51 and the connected throttle valve rod 52 so as to close the throttle and thus 115 shut off the steam.

After the air has passed through the relief valve 59 and through the ports of the control cylinder 64 the relief valve will be automatically closed by spring 62. The system can be tested before the train starts 120 by simply opening the test valve 54^a by manually actuating the handle thereof which is thought apparent from Fig. 1. If desired a register of any approved type may be provided for the purpose of recording, for future reference the number of signals passed or rather the number of times which the system is actuated by engagement by the roll 55 with the cam block 21. 125

By the adoption of my described system 130

the setting of the brakes automatically is assured if, for any reason, the engineer fails to perform his duty.

Having thus described my invention I claim as new and wish to secure by Letters Patent:—

1. A safety device of the type described, including an engineer's reversing lever, latching means for said lever, means for the retention of said latching means in operative position, a compressed air supply means, and means for establishing communication between said latching means and said compressed air supply means, comprising a compressed air chamber arranged upon said engineer's reversing lever, said latching means having its rod member equipped with a piston positioned within said compressed air chamber, the resultant piston rod being adapted to provide for direct engagement with said latch retaining means and a tubular air conducting member communicating with said compressed air

chamber of said latching means, said tubular air conducting member having a flexible 25 tubular connection with said compressed air supply means.

2. A safety device of the type described, including a compressed air supply, an air receiver in communication therewith, means 30 for controlling the air supply therebetween and means for delivering the air supply, comprising a valve block for controlling the passage of air through said delivery means, a rod connected with said valve block and 35 carrying a shoe engaging member, a piston whose rod is rigid with the aforesaid rod, a pipe communicating with said compressed air supply, and a valve for manually controlling the air supply through said pipe 40 to said piston.

JOHN S. CRAWFORD.
